2 SHEETS—SHEET 2.

UNITED STATES PATENT OFFICE.

HUBERT F. KRANTZ, OF NEW YORK, N. Y.

METERING-PANEL.

1,047,085.

Specification of Letters Patent. Patented Dec. 10, 1912.

Application filed October 20, 1911. Serial No. 655,765.

To all whom it may concern:

Be it known that I, HUBERT F. KRANTZ, a citizen of the United States, residing at Brooklyn, in the county of Kings, city and State of New York, have invented certain new and useful Improvements in Metering-Panels, of which the following is a clear, full, and exact description.

This invention relates to meter panel boards, and particularly to that type of board shown in my Patent 961,142 of June 14th 1910.

The object of the invention is to provide a switch connecting the branch circuits with the main circuits, which will cause each circuit to be broken on both of its legs at the same time, at the time of disconnecting the meter from the circuit.

A further object is to provide an improved selective contact mechanism for the connection of meter bars with the individual circuits.

Other objects of the invention relate to the general and special construction and arrangement of parts.

The scope of the invention will be pointed out in the appended claims.

In the accompanying drawings: Figure 1 is a face view of a meter panel built in accordance with this invention. Fig. 2 is an end view of the same, drawn to an enlarged scale. Fig. 3 is a section on line 3—3 Fig. 4. Fig. 4 is a central sectional side elevation of the rings on the drum, the drum being shown in side elevation. Fig. 5 is a section on line 5—5 Fig. 1. Fig. 6 is a top plan view of one of the rings.

As shown in the accompanying drawings, 1 is the back plate of slate, marble or other insulating material.

2 and 3 are the main conductor connections.

4 is the neutral connection.

5 is a switch connecting 2, 3 and 4 with bus bars 6, 7 and 8.

9 is a conductor leading to the meter 10.

11 is a conductor from the meter 10 to a cross bar 12 connected by a fuse 13 with the bus bar 8.

14 is a conductor connected with the meter bar 15 to be hereinafter described.

The parts already described are similar to those shown in my aforesaid United States Letters Patent.

16 and 17 represent branch circuit con-

nections for the two polarities of each branch section 18, one being indicated.

19 and 20 are the fuses for each branch circuit connection, each fuse terminating in a fuse clip, having extended therefrom connector pieces 21, 22 as the case may be, the connector pieces 21 being of greater height than the connector pieces 22, but both being bent over to form ears 23, 23' to be engaged by split jaws 24 mounted on an axially rotatable insulated switch shank 25. The switch blades 24 which connect with the bent end 23 have their other ends turned inwardly as shown at 25, so that they may enter and properly contact with slotted rings 26 hereinafter described. The conductor blades 24 which contact with the ear 23' have their other ends at 27 flared outwardly to engage with a bent-over ear 28 secured to the bar 29, which is one leg of the neutral bar 7. This leg 29 of the neutral bar has its corresponding leg on the other side of the board, as do all the parts described. They are however, placed nearer together than shown in my prior patent, so as to lie below and behind the drum, or rings hereinafter described. As the switch blades 24 are mounted with some distance between, it will be seen that a simple manipulation of the switch will disconnect both sides of the branch circuit.

As shown in my prior patent the meter bars 15 are brought in from the sides of the board, and raised in a series of steps as indicated in Fig. 5, the steps being of different height and entering a drum 30 of insulating material, the bars are arranged along the outside of the drum, and parallel to its axis, each meter bar preferably being of T cross section, and having a dished exposed outer surface 31 with which there may contact a shoe 32 carried by an insulating ring 33. The shoe 32 is held in contact with the bars by a spring 34 surrounding a post 35 passing through a bearing 36 fastened by screws 37 to an extending lug 38 of the ring 26, said ring being provided at equally spaced distances around its circumference with open jaws 39 adapted to be engaged with the contact blades 24 of the switch. The block 32 is so placed with reference to the jaws that it will always connect a given meter bar when one of the jaws 39 is exactly and precisely opposite the switch arm, so that to operate the switch will insure a

proper registry of the connecting shoe with the meter bar. In order to determine which of the meter boards shall be connected with a given switch, and its circuit, numerals may 5 be arranged around the rings as indicated in Fig. 1.

I claim as my invention:

1. The herein described panel board consisting of bus bars, cross bars, meter bars, a 10 movable selective contact device adapted to contact with any given meter bar, said device carrying a plurality of switch engaging contacts, a branch circuit, a double pole switch between the branch circuit and the 15 selective contact device and bus bar, whereby any one of the plurality of switch engaging contacts can be brought into a position to engage with the proper switch contact.

2. The herein described panel board consisting of a back board, bus bars and cross bars, meter bars grouped around a common center, a selective contact device adapted to contact with any one of said meter bars, branch circuits, a double poled switch be- 25 tween the branch circuits and the selective contact device and bus bar, and means carried by the selective contact device to permit the operation of the switch only when the selective contact device is in engage- 30 ment with a meter bar.

3. The herein described panel board consisting of a back board, bus bars and cross bars, meter bars grouped around a common center, a selective contact device adapted 35 to contact with any one of said meter bars, branch circuits, a double poled switch be- tween the branch circuits and the selective contact device and bus bar, and means carried by the selective contact device to per- 40 mit the operation of the switch only when the selective contact device is in engage- ment with a meter bar, said selective contact

device consisting of a metallic ring with slots at predetermined distances on such ring adapted to be engaged by and locked 45 by the switch blade, and a contacting shoe carried by said ring adapted to engage a meter bar when said ring is locked from rotation.

4. The herein described meter panel con- 50 sisting of a back board, bus bars and cross bars, meter bars, a cylindrical drum, a se- lective contact ring movable on said drum, said meter bars being mounted on said drum, a shoe carried by the ring adapted to 55 contact with a meter bar, engagement points spaced about the ring adapted for engage- ment with a switch arm, one of said bus bars having a contact located beneath the point of engagement of the switch and se- 60 lective contact ring, branch circuit contacts in two planes, and a switch having contact arms in two planes, one adapted to engage a branch circuit leg and bus bar connection, and the other adapted to engage a branch 65 circuit leg and selective contact ring.

5. The herein described panel consisting 70 of cross bars, bus bars, meter bars and a se- lective contact device adapted to contact with any one of the meter bars, said contact device being movable, and adapted to be brought into operative position adjacent to a branch circuit connection, a switch be- 75 tween said branch circuit connection and se- lective contact device adapted not only to electrically connect said contact device with branch circuit, but to lock said selective contact device in position.

Signed at Brooklyn, New York, this four-
teenth day of October, 1911.

HUBERT F. KRANTZ.
